CLAIM

The ornamental design for a control panel for air fryer, as shown and described.

DESCRIPTION

FIG. 1 is a front, right side perspective view of a control panel for air fryer showing my new design; FIG. 2 is a front, left side perspective view thereof; and, FIG. 3 is a front view thereof.

The broken lines in the drawing views depict portions and environmental structure of the control panel for air fryer that form no part of the claimed design.
